UNITED STATES PATENT OFFICE.

ROBERT LUNDELL, OF BROOKLYN, NEW YORK, ASSIGNOR TO THE JOHNSON-LUNDELL ELECTRIC COMPANY, OF NEW YORK, N. Y.

ELECTRIC RAILWAY.

SPECIFICATION forming part of Letters Patent No. 560,513, dated May 19, 1896.

Application filed December 6, 1895. Serial No. 571,217. (No model.)

To all whom it may concern:

Be it known that I, ROBERT LUNDELL, a citizen of the United States, residing at Brooklyn, in the county of Kings and State of New York, have made a new and useful Invention in Electric Railways, of which the following is a specification.

My invention relates to that type of electric railways in which the propelling-current is taken from sectional trolley-conductors automatically connected to a main-supply conductor by the presence of a motor-car and again disconnected therefrom as the car passes on its journey, and is particularly directed to improvements upon an invention disclosed in a prior patent granted to me on the 10th day of December, 1895, and numbered 551,334.

My invention has for its objects, first, the rendering of the operation of such a system absolutely safe as regards disconnecting the sectional conductors from the main-supply conductor after a car or train has passed, and, second, the reliability of current supply when such is required to propel the car or train, and particularly the certainty of not losing the propelling-current when running at very high speeds in either direction upon the same track. These objects are accomplished by the apparatus hereinafter described, the novel and essential features being particularly pointed out in the claims at the end of this specification.

Referring to the drawings, Figure 1 is a diagrammatic view illustrating a section of a single-track street-railway, eight sectional trolley or service conductors arranged in two rows parallel to a current main or supply conductor, electromagnetic switching devices and circuit connections between the sectional conductors, the switches, the main-supply conductor and the rails or return-conductor; also a diagrammatic view of a street-car, showing current-collecting devices, car-wheels, a motor, a battery, a switch, circuit connections from the current-collecting devices to the switch, the battery, and the motor, and circuit connection from the negative end of the battery to the car-axle or return-conductor. Fig. 2 is a diagrammatic view illustrating a section of a single-track trunk-line railway

equipped and operated upon the same generic principle as the street-railway, but differing therefrom in some important details regarding the length and location of the sectional trolley-conductors, the size and capacity of the battery and the circuit connections appertaining thereto.

Referring now to the drawings in detail, and first to Fig. 1, FW represents a current-feeder or main-supply conductor and FW' FW² FW³ FW⁴ branch feeders therefrom leading into switch-boxes (not shown on the diagram) and to non-fusible fixed contact-points l, l², l⁴, and l⁶. All of these conductors and parts should be extremely well insulated, inasmuch as they are alive at all times. The opposite contact-points l' l² l⁴ l⁶ are connected through wires w', w², w⁴, and w⁶ to sectional trolley-conductors Sc', Sc², Sc⁴, and Sc⁶, all of which are only successively made alive when current is required to propel the car.

Sc², Sc⁴, Sc⁶, and Sc⁸ are additional sectional trolley-conductors, connected by wires w², w⁴, w⁶, and w⁸ through low-resistance magnet-coils to the track-rails or return-conductors R and R', the arrangement being such that the magnet-coils of adjacent switch-magnets are interconnected by means of the circuits leading from each sectional trolley-conductor Sc² Sc⁴, &c., to the track-rails. These interconnections serve to make the sectional conductors or rails Sc', Sc², Sc⁴, and Sc⁶ alive before they are reached by the traveling contact-shoe S, no matter in which way the car be going, the importance of which will be understood by the description of operation which follows.

The contact-shoes S' and S², carried by the car, are of such length that they will bridge the spaces between two sectional conductors or rails. The contact-shoe S' is connected by means of wire w⁹ to the lever of a switch Sw, which when closed completes connection through wire w¹¹ to the positive pole of a battery B and through wire w¹⁰ to motor M, as shown. The other terminal of the motor is connected through conductor w¹² to contact-shoe S², and the negative pole of the battery B is connected through wire w¹³ directly to the car-axle and return-conductors R and R'.

The operation of the apparatus shown in

Fig. 1 is as follows: Suppose that all the electromagnetic switches are open and that the motorman is just closing the switch S_w . A current will then flow from the positive pole 5 of the battery through wire w^{11} to switch S_w , through resistances and conductor w^{10} , through the motor M and wire w^{12} to contact-shoe S^2 and hence to sectional trolley-conductor Sc^4 , thence by wire w^4 through a coil around 10 the switch-magnet M^2 and also through a coil around switch-magnet M^3 , energizing these two magnets, and finally to track-rails R and R', car-wheels, and negative pole of the battery. The instant this current begins to flow 15 and before the car has had time to start the switch-levers p^2 and p^3 will close connection between the branch feeders Fw^2 Fw^3 and the sectional trolley-conductors Sc^3 and Sc^5 , as shown in the drawings. Owing to the domi- 20 nating electromotive force of the current feeder or main the current will now flow as follows: From current feeder or main FW to branch feeder Fw^2 , through switch-contacts l^2 and l^3 and wire w^3 to sectional trolley-conduc- 25 tor Sc^3 , hence to contact-shoe S' and through wire w^9 to switch S_w , where the current di- 30 vides into two parallel circuits, one flowing through wire w^{11} to the battery B (charging the same) and thence through wire w^{13} to car- axle and return-conductor, the other circuit 35 being by wire w^{10} , through the motor M, conductor w^{12} , contact-shoe S^2 , sectional conductor Sc^4 , wire w^4 , and through the coils of magnets M^2 and M^3 in the same direction as be- 40 fore to track-rails R R' or return-conductor. It will thus be seen that the coils of the magnets M^2 and M^3 are in series with the motor M and that in consequence the switch-levers p^2 and p^3 will remain closed as long as the 45 propelling-current flows through conductor w^4 . If the car be moving from right to left, it will be evident at a glance that the sectional conductors Sc^5 and Sc^7 are made alive in ad- 50 vance of the contact-shoe S' ; but it remains 55 to be seen if this holds true when running in the opposite direction. Suppose the car starts from the position shown and moves to the right instead of to the left. All connections will then remain undisturbed as long as the 60 contact-shoe S^2 is still upon the sectional conductor Sc^4 ; but when the shoe S^2 closes contact with sectional conductor Sc^3 and finally breaks contact at Sc^4 the propelling-current will sim- 65 plly be shifted from wire w^4 to wire w^2 . This, 70 however, energizes magnet M' instead of mag- net M^3 , and magnet M^3 remains undisturbed, leaving the branch feeder Fw^3 in connection with Sc^3 . As the shoe S' now approaches sec- 75 tional conductor Sc' , the lever p' will have 80 closed connection between the branch feeder Fw' and the sectional conductor Sc' , thus illustrating that the system of interconnec- 85 tions between switch-magnets is adapted to work both ways.

65 Upon studying the diagram in Fig. 1 it will be understood that the maximum time allowed for each magnet to close is equal to the time

the car takes to travel the distance between the sectional conductors Sc^2 and Sc' . It will also be noted that the high-potential sectional 70 conductors Sc' , Sc^3 , Sc^5 , and Sc^7 are in direct connection with the contacts l' , l^3 , l^5 , and l^7 in the switch-boxes without any of the coils around the magnets being included in circuit, so that in case the insulation of one of these 75 sectional conductors should become impaired, the leakage-current cannot hold the magnet closed and therefore cannot keep the conductor alive after the car has passed.

In the street-railway system just described 80 the potential difference between the feeder and track-rails has been supposed to be about five hundred volts. The sectional conductors are placed in the road-bed with their upper contact-surfaces slightly higher than the 85 pavement and as well insulated as practicable from the ground. To minimize leakage in wet weather they are made as short as possible, and to prevent any sectional conductor from being alive in front or after the car they 90 are placed at such distances apart that the platforms of the car will safely cover both the conductor which is doing service and the one which is made ready for service. The battery is supposed to be of an electromotive 95 force approximating that of the line, so that it will always be fully charged and ready to do service when called upon. It may also be of such capacity as to be able to propel the 100 car for short distances across turnouts, cross- 105 ings, switches, &c., where the electric equipment of the road-bed would present natural difficulties. The battery will thus propel the car independently of the station-current by closing the switch S_w and also another switch, 110 (not shown in the drawings,) which switch will close a connection between wires w^{12} and w^{13} and which may also be so arranged that it will break connection between switch S_w and the contact-shoe S' .

Upon examination of Fig. 2 it will be noted 115 that the sectional conductors or rails are made much longer and that the conductors or rails Sc^2 , Sc^4 , and Sc^6 are placed on the outside of the track-rails, the object of so placing being 120 to obtain additional safety against leakage from the high-potential rails Sc' Sc^3 Sc^5 . These rails are to be supported on good insulators, which in turn are supported on the cross-ties. Suppose, for illustration, that the 125 difference of potential between feeder and re- turn rails is one thousand volts and that the locomotive shown in diagram is capable of exerting a maximum power of one thousand horse-power or seven hundred and fifty kilo- 130 watts. Under these conditions it would of course be absurd to employ a battery to move the train. The battery in this case is therefore of a capacity sufficient to close the electromagnetic switching devices and to keep the same closed in case the locomotive should happen to take an unusually small current. The arrangement of circuit connections is, however, such that after the original closing

the main current operates the electromagnetic switches and at the same time charges the battery.

The operation is as follows: Suppose the locomotive is at rest and that all the switches are open. Upon closing the switch S_w a current will flow from the positive pole of battery B through wire w^{11} to switch S_w , hence by wire w^{12} , contact-shoe S^2 to sectional conductor or rail Sc^4 , by conductor w^4 through a coil of magnet M^2 , and also through a coil of magnet M^3 , and finally by track-rails, car-axle, wire w^{13} to the negative pole of the battery. The magnets M^2 and M^3 are now energized and levers p^2 and p^3 have established connection between the branch feeders $Fw^2 Fw^3$ and the sectional conductors or rails $Sc^3 Sc^5$, as shown in the drawings. The current now flows as follows: From branch feeder Fw^3 by wire w^5 , sectional conductor or rail Sc^5 , contact-shoe S' , wire w^9 , through the motors M, by wire w^{10} , through starting resistances and switch S_w , where it divides itself, one part of the current flowing by way of wire w^{12} to shoe S^2 , sectional rail Sc^4 , wire w^4 , around both magnet-coils, as at the instant before, and, finally, to track-rails R and R' back to the generating-station. The other part of the current flows by wire w^{11} through the battery B, charging the same, and by wire w^{13} to car-axle CW and track-rails. To fully appreciate the automatic charge or discharge of the battery, as the case may be, it will be necessary to illustrate the operation with a few figures. Suppose the battery B consists of five cells of large ampere capacity. The electro-motive force of discharge will then be about ten volts, whereas the counter electromotive force at charging will be about $5 \times 2.5 = 12.5$ volts. Assume the sum of all the resistances included in the circuit w^{12} , contact-shoe S^2 , sectional conductor or rail Sc^4 , wire w^4 , two electromagnetic-coils $M^2 M^3$ to the negative pole of the battery B to be .05 ohms. Upon closing the switch, the battery will then send a current of $\frac{10}{.05} = 200$ amperes through this circuit.

In case the current from the main-supply conductor flowing through the motors and starting the same should happen to be two hundred amperes, no current will flow through the battery, nor will any appreciable amount of current flow through the same until the current has increased to two hundred and fifty amperes when the electro-motive force at the battery-terminals has risen to 12.5 volts; but if the motors should take about five hundred amperes about half of this current will flow through the battery, charging the same. At the same time, if the train should run down a grade and happen to take so small a current that there is danger of not having sufficient number of ampere-turns around the magnets to keep them properly energized, then the battery will at once make up the difference between two hundred amperes and the current taken by the motors.

To illustrate the importance of the interconnections between the magnets, let us assume that the locomotive shown in Fig. 2 is moving from left to right at a speed of sixty miles per hour, or eighty-eight feet per second. As the shoe S' is traveling over the sectional conductor or rail Sc^5 and shoe S^2 is leaving sectional conductor or rail Sc^6 and commencing to travel upon conductor or rail Sc^4 , the current is shifted from wire w^6 to wire w^4 and the magnet M^2 is in condition to close its switching-lever p^2 ; but when the shoe S' leaves rail Sc^5 the magnet M^2 must be closed and conductor or rail Sc^3 must be alive or the propelling-current would be broken at the end of rail Sc^5 . Now, if the magnets are made to safely close in one-half a second, it follows that the distance D (see Fig. 2) must be about forty-four feet. Should the train move at still greater speeds, it will be necessary either to construct electromagnets that will operate in less than one-half second or to make the sectional rails longer, or to increase the length of the contact-shoes.

Having thus described my invention, what I claim, and desire to secure by Letters Patent of the United States, is—

1. In an electric railway a system of permanent or continuous interconnections between electromagnetic switches and sectional trolley-conductors, the arrangement being such that each electromagnetic switch is given a certain time allowance to close before it is called upon to transmit the propelling-current no matter which way the car or train be moving.

2. The combination of switch-operating electromagnets with two sets of sectional trolley-conductors, the coils of said magnets being permanently in circuit between one set of said sectional conductors and the ground or return conductor and when energized included in series with the motor; the other set of said sectional conductors being temporarily connected to a current feeder or main directly through the switch-contacts while a car is passing and wholly disconnected from the switch-operating magnets after the car has passed.

3. In an electric-railway system a current feeder or main, a series of sectional trolley-conductors, electromagnetic switches for connecting said sectional conductors to the current feeder or main in sequence as a car or vehicle moves over them in either direction, a battery and a motor carried by the car for operating the switch-electromagnets and propelling the car; said electromagnets being permanently or continuously interconnected in series relation so as to connect up the sectional conductors to the feeder before the propelling-current is connected in circuit with the motor, substantially as described.

4. In an electric-railway system a current feeder or main, a series of sectional trolley-conductors, electromagnetic switches for connecting said sectional conductors to the cur-

rent feeder or main as a car passes over them; the electromagnets being permanently or continuously interconnected with each other and the sectional conductors, so that each of the conductors which is designed to carry the propelling-current to a propelling-motor carried by the car, shall be connected to the current-feeder before it is connected to the motor, the connections and arrangement being such that the car may run in either direction with equal facility, substantially as described.

5. In an electric-railway system a current feeder or main, two rows of sectional trolley-

conductors, permanently or continuously interconnected, electromagnetic switching devices in combination with a return conductor or rail located between said rows of sectional trolley-conductors, substantially as described.

In testimony whereof I have hereunto subscribed my name this 4th day of December, 1895.

ROBERT LUNDELL.
